UNITED STATES PATENT OFFICE.

WILLIAM W. LASKER, OF BROOKLYN, NEW YORK, ASSIGNOR TO POWERS ACCOUNT-
ING MACHINE COMPANY, OF NEW YORK, N. Y., A CORPORATION OF DELAWARE.

CARRIAGE OPERATING MECHANISM.

1,423,437.

Specification of Letters Patent. Patented July 18, 1922.

Original application filed March 28, 1917, Serial No. 158,142. Divided and this application filed January 30, 1918. Serial No. 214,478.

To all whom it may concern:

Be it known that I, WILLIAM W. LASKER, a citizen of the United States, residing in Brooklyn, in the county of Kings and State 5 of New York, have invented certain new and useful Improvements in Carriage-Operating Mechanism, of which the following is a specification.

This invention relates to a printing tabulator of the kind adapted to be controlled by perforated cards, and relates more particularly to matter divided from my copending application Serial No. 158,142 filed March 28, 1917, for printing tabulators.

15 The invention herein described relates more particularly to the carriage operating mechanism of said printing tabulator; and, therefore, only as much of the printing tabulator is described herein as is necessary to 20 show the connection between the matter of the original application and the matter divided out and described herein.

While herein and in said application minute details of one of many possible embodiments of the invention are described, the invention is not limited to these since various changes may be made in the details of construction and combination without departing from the spirit and scope of the invention as claimed.

One object of the invention is to improve generally apparatus of this kind.

Another object of the invention is to provide an economical and efficient means for 35 effecting the printing by the reciprocation of the paper carriage when the printing type have been set.

Another object is to provide convenient means for rendering the carriage reciprocating mechanism inoperative at will and for automatically rendering the reciprocating mechanism operative when totals are printed.

Another object is to provide convenient means for at will displacing the printing carriage laterally relative to the type so that substantially any part of the paper may be brought to the type.

Another object is to provide an efficient and convenient total signal means for indicating the fact that a figure is a total, this

means operating by shifting the carriage to one side as the total is being printed, whereby the total is offset from the listed column.

Still further objects and advantages of 55 the present improvement will be set forth in the following description and drawings in which,

Fig. 1 is a side elevation of the printing and calculating mechanism constituting a 60 part of the printing tabulator.

Fig. 2 is an end elevation of the printing carriage showing one position of the parts.

Fig. 3 is a similar view, parts being broken away showing a different position of the 65 parts.

Fig. 4 is a front elevation of the carriage.

Fig. 5 is a sectional view of the detail taken on the lines 5—5 of Fig. 38.

Fig. 6 is a fragmental end elevation showing parts of the paper feeding mechanism and the release of the same.

Figs. 7 and 8 show sections taken respectively on lines 7—7 and 8—8 of Fig. 40.

Fig. 9 is a face view of the print and non-print laying plate.

The invention herein relates to a printing tabulator which is adapted to be actuated by perforated cards, which in their passage through the machine operate elements for setting up type commensurate with the designations on the card and actuate an accumulating mechanism for accumulating therein the data recorded on the card perforations whereby the total accumulated data may be computed and then printed by the printing elements of the machine.

In said co-pending application there is described a machine which comprises a main frame, a main driving shaft 2, a card feeding mechanism, a card analyzing mechanism.

Power is suitably transmitted to the cam shaft 17 provided with a plurality of cams from which are operated, as explained in 95 said co-pending application, the various mechanisms of the tabulating machine 19, of which it suffices here to say that these are controlled by the cards fed to the analyzer and operate the type segments 20 so that 100 the type 21 will be positioned to print items and totals, in accordance with the cards an-

alyzed, upon a sheet of paper brought against the type by the printing carriage now to be described.

The printing carriage, designated generally by reference numeral 28 (Figs. 1, 2 and 3) is located on the rear of the printer tabulator base, to the rear of the tabulating machine 19.

The carriage is supported, at opposite ends, on the cam shaft brackets 29 and the lever shaft brackets 31 carried on the base plate of the printer tabulator. These brackets are tied together at their upper part by the tie plates 32 bolted at opposite ends 15 to the upper part of these brackets respectively.

The lever shaft brackets 31 are provided at their upper ends with guide slots 34 in which are received the L shaped carriage supporting brackets 35 provided at their forward ends with anti-friction rollers 36 adapted to reciprocate in the elongated openings 37 of the cam shaft brackets.

The supporting brackets 35 are formed near their rear ends with uprights 38 between the upper ends of which are carried the rail supporting bar 39. Between the rear ends of said supporting brackets is carried the arm supporting shaft 40 intermediate of the ends of which are carried the L shaped supporting members 42 comprising the forwardly extending carriage supporting arms 44.

Intermediately of the ends of the supporting bar 39 are carried the forwardly projecting plates 45 which carry at their forward ends the carriage rail 46.

The carriage proper comprises end plates 47 held spaced apart by the tie rod 48 and the bracket shafts 49. On the bracket shafts are mounted the rearwardly extending supporting brackets 50 each provided with a circular opening adapted to receive the carriage rail 46, this opening being provided with a rearwardly extending slot 51 adapted to provide a passage for the projecting plates 45 when the carriage is slipped on to the carriage rail. When the carriage has been put in place it is thus supported by said carriage rails and by the forward ends of the arms 44 engaging under the tie rod 48 at the lower forward part of the carriage.

Between the end plates 47 is mounted the paper roller shaft 60 carrying part of the paper supporting and feeding mechanism to be described more in detail thereafter.

In the operation of the machine it is sometimes desirable to shift the carriage longitudinally relatively to the type sector units, so that the printed column may occupy any desired position upon the sheet of paper. Means for accomplishing this will now be described:

The forward edge of the uprights 38 (Figs. 2 and 3) of the brackets 35 are pro-

vided with inwardly turned perforated ears 61 (Fig. 5) carrying supporting studs 62 on which are slidably mounted the locating bar 64 provided with elongated slots 65 receiving said studs, said bar being also provided with a plurality of holes 66 large enough to receive the heads of the locating stud 67 fixed on the locating bracket 68 fixed to the shaft brackets 29 (Fig. 3) connecting the end plates 47.

The carriage may be swung outwardly upon the rail 46 (Fig. 3) until the stud 67 clears the holes 66 (Fig. 5) and the carriage then shifted longitudinally until the stud engages in a different hole 66, as desired. The stud 67 and bracket 68 are locked in the adjusted position by means of a locking plate 70 provided with key slots 71 each having a large end 72 through which the head of the stud 67 is adapted to pass and with small ends 74 adapted to form shoulders to engage under the heads of said studs whereby the stud is locked in position by means of a spring 75 tensioned between the upright 38 and the angular manipulating end 76 bent outwardly from said locking plate.

The locking plate 70 is held in proper position by means of the guide plates 79 and 80, the guide plate 79 being secured to one of said ears 61 and engaging over the locking plate, the guide plate 80 being secured to the manipulating end 76 of the locking plate and provided with a slot 81 receiving a screw 82 secured to the adjacent ear 61.

The printing is accomplished by the forward movement of the paper supporting mechanism which movement brings the paper against type 21 of the type sectors. This is accomplished by means of the upper and lower carriage actuating levers 87 and 88 (Fig. 3) pivoted on the lever shaft 89 carried by lever shaft brackets 31. The upper and lower actuating levers are both pivotally mounted on said shaft 89 and when in printing position are locked together as will be explained, and are oscillated by means of the engagement of the cam roller 90 engaging in the cam groove 91 of the printing cam 92 carried on the cam 17. The actuating levers give one complete cycle of oscillation once for every revolution of the cam shaft 17.

The locking above referred to is accomplished by means of locking cones 95 which are shown in unlocked position in Fig. 4 and must be moved to the right of said figure to lock said upper and lower levers against relative movement. These cones engage in, and when locked, hold in alignment the openings 98 and 99 of said upper and lower levers, and are carried on the cone supporting shaft 100 yieldably drawn to unlocked position by means of the tension spring 101 secured between the end of said shaft and a cross piece 102 (Fig. 3) disposed across the opening 104 in the lever bracket 31. The

opening 104 is large enough for the insertion of the cone shaft and cones when assembling the machine. These cones may be moved to locking position by means of the bell crank lever 105 fulcrumed on the base of the machine and provided at its upper end with spaced ears 106 engaging a transverse pin 107 in the cone supporting shaft 100. This lever is actuated by means of a link 108 pivoted at its lower end to said lever 105 and at its upper end to the locking lever 110 (Figs. 1 and 2) fulcrumed intermediately as at 111 on the cam shaft bracket 29. The locking lever 110 terminates in a manipulating end 112 (Figs. 2 and 9) received in a slot 114 of the locking plate 115, said slot being provided at its upper and lower parts with shoulder forming recesses 116 and 117 in which said manipulating end may be 20 locked to retain said locking cones in either locked or unlocked position.

Now will be described the means for supporting the paper on the carriage. On the paper roller shaft 60 journaled in the end plates 47 (Figs. 4 and 8) are disposed a plurality of paper rollers 118 each provided with a boss 119 held spaced apart by means of spacing bushings 120 (Fig. 7). Between adjacent pairs of the paper rollers and 30 loosely engaging said bushings are disposed platen support brackets 121 held against rotation by means of the bracket shaft 122 passing through perforations in the lug 123 on the upper part of said brackets, said 35 brackets being held in spaced relation by means of sleeves 124 (Fig. 8) carried on said shaft 122. The lower part of each platen support bracket carries a forward projection 125 on which is secured as by 40 means of a screw 126, the platen support 127 having a recess in its forward end in which is carried the elastic platen block 128 of rubber or other suitable material.

The bushings 120 hold the paper rollers 45 out of frictional contact with the platen brackets. The bushings and the paper rollers and all the parts rotatable on the paper roller shaft 60 are caused to rotate with said shaft by means of frictional engagement with each other brought about by the clamping of the screw 129 (Fig. 3) on said shaft.

Between each adjacent pair of paper rollers are the upper and lower inner paper 55 shields 130 and 131 (Fig. 7) which form a continuation of the cylindrical surface of the paper rollers. These shields have angular extensions 134, each extension having inwardly turned ears 135, each provided 60 with an opening receiving the bracket shaft 122. The upper inner shield 130 is pivotally supported on said rod by said ears, being permitted to move pivotally because of the rounded upper face 136, whereby access

may be had to the screw 126. This upper 65 shield 130 may be omitted if desired.

Partly surrounding or housing the lower inner shields 131 and the lower part of the paper rollers 118 are the outer paper shields 137 provided with edge flanges 138 on which 70 are formed, turned ears 139 provided with openings receiving the bracket shafts 29 (Figs. 3 and 7).

These outer shields cooperate with the lower inner shields 131 to form guides for 75 the paper 140 on which the tabulations are to be printed, the outer shields being continued upwardly in front of the paper rollers 118, whereby are formed extensions 144 (Fig. 6) between which the type of the 80 type sectors pass when the paper is pressed against them by means of the platen blocks 128.

On the lower part of the flanges 138 are formed small ears 145 provided with perforations in which are carried release arm shafts 146 (Figs. 6 and 7) on which are pivotally carried the feed roller levers 147 between the outer ends of which are journaled the paper feed rollers 148, said roller engaging on opposite sides of the lower part of the paper rollers 118, and passing through suitable openings in the lower shields 137. These feed rollers are held in contact with the paper rollers by means of feed roller tension springs 149 secured at opposite ends to the journaled pins 150 of the rollers (Figs. 4 and 6). The inner ends of the feed roller levers are provided with inwardly pointing fingers 153 engaging over the release rod 100 154 guided in elongated slots 155 in the end pieces 47 (Fig. 3). When this release rod is raised the feed rollers 148 are moved to the position of the dotted lines of Fig. 6, out of contact with the paper rollers, for 105 permitting the removal of the paper. This raising of the release rod is accomplished by means of release arms 156 mounted on the release arm shaft 157 carried in the end plates 47 and actuated by the release lever 110 158 (Fig. 2) adapted to be caught behind the shoulder 159 of the inturned lug 160 on the end plate 47, to hold the rollers in released position.

After each number is printed by the type 115 of the type sectors, it is necessary to feed the paper upwardly one or more spaces. This feeding is accomplished by means of engagement of the teeth of the feed ratchet 161, mounted on the shaft 60, by a two 120 armed feed pawl 162 (Fig. 3) pivotally mounted on the feed pawl lever 164 fulcrumed intermediately as on the stud shaft 165 and driven by the link 166, in turn driven by the drive lever 167 mounted on 125 the feed shaft 168, said shaft being actuated by the actuating arm 169 fixed on said shaft and adapted to come into contact with

and be moved by the abutment shaft 170 carried on the abutment shaft bracket 171 pivotally mounted on the tie plates 32. The brackets 171 are limited in their rearward movement by the engagement, with the tie plates 32 of a shoulder 172 formed by the lower edge of the lug 174 laterally turned at the rear edge of said abutment shaft brackets, and is yieldably held at its rearward limit of movement by a spring 175 tensioned between said lug 174 and a lug on the rear part of the shaft tie plate 32.

When the carriage is moved forwardly toward the type sectors the free end face 176 of the actuating arm 169 engage and push forwardly and rearwardly the abutment shaft 170 against the action of the spring 175 until said end face clears said shaft and permits the shaft and its brackets 20 to be snapped back by the spring 175 until stopped by the shoulders 172.

Fig. 3 shows the abutment shaft while being snapped back the instant after it has cleared said end face.

25 After the printing has taken place and the carriage moved rearwardly, the abutment shaft 170 is engaged by the lower side 173 of the actuating arm 169 whereby said arm and drive lever 167 are raised thus rocking the pawl lever 164 and lowering the pawl 162, thus turning the ratchet 161 one of more teeth depending upon how soon the lower member 177 of the pawl is permitted to engage the teeth. When it is desired that the 30 ratchet feed only one tooth at a time, the feed limiting lever 178 pivotally mounted on the upper part of the end plate 47, is set in the position shown in Fig. 3, thus preventing the lower member 177 to continue 35 to engage the ratchet teeth after it has moved upwardly a distance of one tooth, since the inclined inner face 179 of said member will be engaged by the feed limiting pin 180 mounted on the lower part of the 40 feed limiting lever.

The feed limiting lever 178 is somewhat resilient and is provided with a pair of depressions 181 either one of which is adapted to be engaged by a single projection on the 45 inner face of the end plate 47, depending upon whether the lever is shifted to the right as shown in Fig. 3, or to the left. This arrangement serves to hold the lever in shifted position.

50 When it is desired that the pawl feed more than one tooth of the ratchet at a time, the lever 178 is shifted to the left of Fig. 3 thus moving the pin 180 away from the lever pawl member 177 permitting said member 55 to be in engagement with the ratchet teeth during the downward movement of the pawl member for a distance of, for instance, two teeth. If desired, the parts may be so proportioned that three or more teeth may be fed at a time.

In order to prevent the feeding of the carriage more than the desired number of teeth, as when the machine is running at very high speed, the pawl 162 is provided with an overthrow preventing cam 182 70 adapted to engage between the teeth of the ratchet and the inclined face thereof, whereby the ratchet is prevented from turning another tooth space after this pawl has ceased to travel in its feeding direction. A 75 spring 184 tensioned between the stop member 822 and the lever 804 yieldably holds the pawl in engagement with the ratchet teeth.

The feeding mechanism is yieldably held in position to feed by means of a spring 185 80 tensioned between the end plate 47 and a perforated ear on the upper part of the inner end of the arm 167.

In order to hold the ratchet wheel 801 and the parts carried on the shaft 60 in the positions in which they are fed by the pawl, I provide a detent roller 186 revolvably mounted on one end of the detent lever 187 pivoted to the end plate 47 and drawn by the spring 186 strained between the other end of the 90 detent lever and the lower part of the end plate 47, whereby said roller is yieldably pressed between the teeth of the ratchet and yieldably holds the ratchet in the position to which it is fed. 95

When it is desired to insert, remove or feed the paper entirely independently of the feeding mechanism just described, I provide the mechanism, shown in Fig. 4 comprising the paper feed gear 189 fixed on the paper feed shaft 60 and engaged by the idler gear 190 rotatably mounted on the end plate 47, the idler gear being in turn engaged by the knob gear 191 fixed on the stud shaft 165 rotatably mounted in the end plate 47 and 105 carrying knurled knob 192 by which said shaft and gears may be manually rotated.

While the paper is being fed and during the time of printing, it is desirable that it be firmly held against the platens. This is 110 accomplished by means of a clamping mechanism comprising a clamp bar 193 (Fig. 3) carried between the outer ends of the clamping levers 194 provided with intermediate longitudinal slots 195 loosely receiving the 115 paper feed shaft 60, whereby the paper clamp bar is adapted to move toward and from the paper rollers as well as to revolve with said rollers. The inner ends of the clamping levers are provided with small pins 196 received in longitudinal slots 197 in the lower ends of the spring levers 198 intermediately fulcrumed on the end plates 47 and drawn by a spring 199 strained between the upper end of the spring levers and the 125 upper part of end plates 47, whereby the clamp lever 194 is yieldably drawn downwardly and the clamp bar 193 is yieldably pressed against the paper and the paper 130 pressed against the paper rolls 118.

This yieldable engagement maintains during the printing and feeding of the paper, but after feeding has taken place, as above described, the releasing pin 200 mounted on 5 the cam bracket shaft 201 comes into contact with the abutment shaft 170 and forces the cam bracket shaft and the cam bracket 202 to rock rearwardly whereupon the cam edge 203 forces outwardly the pin 196 and therefore 10 with the lever 194 and bar 193 and also rocks said lever in a direction clockwise on Fig. 3 whereupon the bar 193 is moved downwardly over the paper and later takes a fresh grip upon the paper when the clamping 15 lever is released by the cam on the next forward movement of the carriage and moves downwardly under the action of the spring 199.

The upper part of the cam brackets 202 20 are each provided with an outwardly projecting ribbon feed arm 204 (Fig. 2) for operating the feed mechanism of the ribbon spools 205 carrying the ribbon 206 (Fig. 4); but as these form no part of the invention 25 claimed herein they are not now further described.

When a total is printed it is desirable to show some visual signal to indicate that the number printed is a total. This is accomplished by shifting the carriage to the 30 left when the total is printed, whereby the total is shown printed a little to the right of the alignment of the listed column.

Means for accomplishing this result will 35 now be described.

As shown in Fig. 4, the lower edge of the locating bar 64 is provided with a notch 240 in which engages the upper end of the vertical lever 241 pivoted intermediately on the 40 bracket 242 fixed on the printing lever shaft 89, the lower end of said lever being pivotally connected to the rear end of the horizontal lever 244 (Fig. 2) intermediately pivoted on a pin 245 in a lug 246 on the 45 base of the machine. The forward end of said horizontal lever is pivotally connected to the rear end of the total shift lever 252.

When a total is to be taken the total pin 253 engages in the appropriate cam groove, 50 said pin is shifted to the right, and a total is set up on the type 21 all as explained in said co-pending application and the upper end of the lever 242 (Fig. 4) is shifted to the left whereupon the locating bar 64 55 is moved to the left on the pin 62 (Fig. 5) in the slot 63, thus causing the printing to take place a slight distance to the right of the column.

When by means of the lever 110 the carriage has been set to a non-printing position 60 so that the items accumulated and set up by the type 21, are not printed, it is still desirable that the totals themselves be printed. In order to accomplish this printing automatically, there is provided the automatic

printing lock lever 257 (Fig. 4) pivotally mounted on the bracket 258 fixed to the shaft 89, the upper end of which lever engages in a notch 260 the lower end engaging a transverse pin 261 in the printing lock shaft 100. 70 When the carriage is shifted to the left, the bar 64 is moved therewith and carries the upper end of the lever 257 to the left whereupon the lower part of said lever, said printing lock shaft and the cones 95 are moved 75 to the left thus locking together the upper and lower printing levers 87 and 88 and effecting the printing.

From the foregoing, the operation of the printing carriage will be easily understood. 80 Paper is inserted in the rear opening between the outer shields 137 and the inner lower paper shields 131, and the paper rolls 118 turned by means of the knob 192 until the part on which it is desired first to print are 85 opposite the platen blocks 128. The feed limiting lever 178 is set for the number of teeth it is desired that the feed ratchet shall be fed. If desired the locking plate 70 is unlocked and the carriage adjusted on the 90 carriage rail and the carriage relocked.

The locking lever 110 is set in locked or unlocked position depending upon whether it is desired that the items be printed or not. 95

The tabulating machine is then started in operation as explained in the said co-pending application and the type is set and the accumulators accumulate. If the locking lever is set in locked position the cams 92 100 cause the printing levers and the carriage to reciprocate and the printing is effected.

When a total is taken the carriage is moved to the left just before the printing by means of the total signal lever 241 engaging in the 105 notch 240 of the locating bar. If the locking lever 110 has not been set in printing position, the automatic levers 251 also cause the cones 95 to lock the printing levers and print totals when the totals are set up and printed. 110

I claim as my invention:

1. In an apparatus of the character described, the combination of a carriage; a two part lever having the one part operatively connected to the carriage; means for reciprocating the other part only of the lever; and means for at will locking said parts together. 115

2. In an apparatus of the character described, the combination of a carriage; a 120 lever comprising two parts having openings adapted to be aligned with each other; means operatively connecting the carriage to one of said parts; means for reciprocating the other of said parts; and means adapted to be passed 125 through said openings to lock said parts together.

3. In an apparatus of the character described, the combination of a carriage; levers each comprising two parts having openings 130

adapted to be alined with each other; means operatively connecting the carriage to one of said parts; means for reciprocating the other of said parts; cones adapted to be passed through said openings when said openings are alined with each other to lock said parts together; means for yieldably drawing said cones out of locking position; and means for at will drawing said cones 10 into locking position.

4. In an apparatus of the character described, the combination of a carriage; levers each comprising two parts having openings adapted to be alined with each other; means operatively connecting the carriage to one of said parts; means for reciprocating the other of said parts; cones adapted to be passed through said openings when said openings are alined with each other to lock 20 said parts together; means for yieldably

drawing said cones out of locking position; means for at will drawing said cones into locking position; and means for locking the last named means in either locked or unlocked position.

25

5. In an apparatus of the character described, the combination of a carriage; a printing means; a reciprocating means comprising a two-part lever for moving the carriage away from the printing means and 30 moving it positively toward the printing means; and means for at will locking together or unlocking said parts for rendering said reciprocating means operative or inoperative whereby the carriage ceases to re- 35 ciprocate.

WILLIAM W. LASKER.
